UNITED STATES PATENT OFFICE.

OTTO SELG, OF NEW YORK, N. Y.

BOTTLE-FILLING MACHINE.

SPECIFICATION forming part of Letters Patent No. 784,234, dated March 7, 1905.

Application filed November 7, 1904. Serial No. 231,652.

To all whom it may concern:

Be it known that I, OTTO SELG, a citizen of the United States, residing in New York city, (Brooklyn,) county of Kings, and State of New York, have invented new and useful Improvements in Bottle-Filling Machines, of which the following is a specification.

This invention relates to a machine for charging bottles with liquids under pressure in a simple, quick, and economical manner.

The machine is particularly designed for bottling beer; but it may also be used for filling of other liquids.

In the accompanying drawings, Figure 1 is a side elevation of my improved bottle-filling machine; Fig. 2, a similar view showing the case reversed; Fig. 3, a plan of Fig. 1; Fig. 4, a detail of the detent; Fig. 5, a detail longitudinal section through the nozzle and adjoining parts; Fig. 6, a cross-section on line 6--6, Fig. 5; and Fig. 7, a detail of the bottle-supporting base.

The letter *a* represents a box or case divided by rectangular partitions *a'* *a''* into a series of compartments *a''*, each adapted for the reception of the lower part of a bottle *A*. The case *a* is provided with arms *a'*, which are fulcrumed at *b'* to a pair of standards *b*, that constitute a fixed frame, so that the case *a* is reversible. To the case *a* is connected in manner hereinafter described a filler which locks the bottles *A* to the case *a* and also serves to convey the liquid into the bottles. The filler consists of a central transverse pipe *c*, into which open a number of parallel longitudinal pipes *c'*, which are so arranged that each pipe *c'* is located above a longitudinal row of bottles *A*. The pipe *c* receives the beer or other liquid from a receptacle (not shown) by a flexible tube *d*, having cock *d'*.

Above each bottle *A* the pipes *c'* are provided with a threaded nipple *c''*, engaged by the threaded upper end of the nozzle *e*, that may be readily rotated by handles *e'* to couple the nozzle to the nipple. Between nipple *c''* and nozzle *e* a suitable packing *e''* is interposed. The nozzle *e* has a bore *e''*, which is enlarged at its upper end to form a valve-chamber *e'''*. This chamber has a tapering base *e''''*, which constitutes the lower seat of a check-valve or

drop-valve *f*, playing freely within valve-chamber *e'''* and adapted to be opened or closed by the reversal of case *a*. Into the upper end of chamber *e'''* project a number of radial fingers *e'''*, that form an open seat for the valve *f* when the nozzle is reversed. The valve *f* is centered by its stem *f'*, that projects into the nipple *c''* and also into the bore *e''*. The stem *f'* is grooved longitudinally at its top and bottom to form ducts *f''*, adapted for the flow of the liquid along the stem. At its bottom the nozzle *e* contains a flexible packing *g*, against which the head of bottle *A* bears.

The valve *f* has a longitudinal bore and communicates with a vent-tube *f''*, made integral with the valve and extending above and below the same. The lower section of the tube *f''* passes through bore *e''* to a point slightly above the bottom of bottle *A*, Fig. 7. The upper section of tube *f''* passes through nipple *c''* and pipe *c* into a stuffing-box *c'''* of the latter. Near its top the pipe *f''* has a lateral opening *f'''*, which is closed by the stuffing-box when the filler is righted, Figs. 1 and 5, but projects beyond the stuffing-box and is consequently opened when the filler is reversed, Fig. 2.

In order to connect the filler to case *a*, the arms *a'* of the latter are provided with teeth *a''* to constitute racks. These racks are embraced by yokes *h*, which are secured to the ends of transverse pipe *c*. Within the shanks of yokes *h* is journaled a shaft *i*, rotatable by handle *i'*. Upon this shaft there is mounted within each of the yokes *h* a pinion *i''*, engaging rack *a''*. To one of the yokes *h* is pivoted at *h'* a pawl *h''*, that engages a ratchet-wheel *i'''*, fast on shaft *i*.

In use the empty bottles *A* are placed into case *a* while the latter is swung down, and then the filler is lowered upon the bottles by turning handle *i'* until a tight joint is formed between the bottle-heads and the packing *g*, Fig. 1. In this position the filler is locked to the case by the pawl *h''* and ratchet-wheel *i'''*, so that consequently the bottles are also locked to the case. The case *a*, together with the bottles and the filler, is now reversed, Fig. 2, which will cause the valves *f* to open by descending upon the pins or open valve-

seat e^6 . The cock d' being open, the beer or other liquid under pressure will now flow through tube d , pipes $c c'$, nipples c^2 , lower ducts f^2 , into chambers e^4 , around valves f , and through upper ducts f^2 and bores e^3 into bottles A. During this operation the air will escape through vent-tubes f^3 , which are now open. After the bottles have been charged the case is again righted, when the escape of beer from the nozzles e will be prevented by the closing of the valves f against seats e^5 . The pawl h^2 is now thrown out of engagement with ratchet-wheel i^3 , and the filler is raised off the bottles. The latter are removed from the case and are closed by stoppers, when the operation is completed.

The frame a may be locked in either of its two positions in suitable manner, such as by a pin inserted into perforations b^2 a^6 of standards b and arms a^4 , respectively.

I prefer to seat the bottle A upon a flexible base l , influenced by a spring l' and contained within the compartment a^3 of case a . These bases press the bottles against the washers g and compensate for slight irregularities in the heights of the bottles.

It will be seen that by the construction described the beer is automatically admitted into the bottles and shut off therefrom by the simple reversal of case a , which causes the automatic opening or closing of the drop-valves. In this way all separate manipulations of the means for controlling the flow of the beer are dispensed with. Further, in the old style of filling-machines the beer had to be carried to a point directly above the bottom by means of a filling-pipe in order to prevent foaming. These pipes were apt to become soiled by the deposit of sediments and required frequent

cleaning. With my machine the foaming is prevented by directing the entering stream of beer in an upright direction into the lower end of the reversed bottle, so that the use of the filling-pipes is avoided.

What I claim is—

1. A bottle-filling machine provided with a reversible bottle-receiving case, a filler, a nozzle on the filler having a valve-chamber, a drop-valve movable within said chamber by the reversal of the case, and means for coupling the filler to the case, substantially as specified.

2. A bottle-filling machine provided with a reversible bottle-receiving case, a filler, a nozzle on the filler having a valve-chamber, a tubular drop-valve movable within said chamber by the reversal of the case, a vent-pipe communicating with the bore of the valve and adapted to be projected into the bottle, and means for coupling the filler to the case, substantially as specified.

3. A bottle-filling machine provided with a reversible case having a series of compartments, a filler composed of a series of parallel pipes and a connecting-pipe, nozzles having valve-chambers and projecting from the filler, drop-valves movable within the chambers by the reversal of the case, and means for coupling the filler to the case, substantially as specified.

Signed by me at New York, (Manhattan,) State of New York, this 31st day of October, 1904.

OTTO SELG.
